HAT STAY

Martin Jacobi, Buffalo, N. Y.

Application January 29, 1948, Serial No. 5,019

1 Claim. (Cl. 2—185)

1

This invention relates to a form or shape retainer for a hat and more particularly to a hat stay to retain the shape of the upper front top portion of the crown of a soft felt man's hat of the fedora type.

It is conventional with such hats to indent the top of the crown and to indent also the front lateral sides of the crown adjacent the top thereof. A hat so shaped is generally placed on and removed from the head of the wearer by grasping the upper top portion of the crown in such manner that the thumb and index finger engage the indented portions of the crown on the lateral sides thereof and the first finger engages the front of the top indented portion of the crown. When a hat so shaped is worn it is occasionally adjusted or pressed down tighter onto the head of the wearer, this readjustment also usually being accomplished by grasping the crown of the hat by the first three digits in the manner described above. With such continued use of a hat the front crest of the crown becomes creased or is gradually lowered so that the shape of the hat is altered and the hat acquires a battered and worn appearance from this manner of grasping the hat as well as a result of being crushed or bumped against objects and the like.

Accordingly it is the principal object of the present invention to provide a hat stay for retaining the shape of the front and upper front portions of a man's hat of the fedora type and which is inconspicuous from the exterior of the hat, readily conformable to the generally oval shape of the wearer's head and causes no discomfort to the wearer, maintains the elevation of the crest of the front portion of the hat crown, is retained in operative position in a manner not injurious to the hat, and can be quickly inserted and removed from the hat as desired.

Another object is to provide such a hat stay which when mounted in a hat will stay in place and will maintain the elevation of the crest of the front portion of the hat crown and prevent the front of the hat from slanting rearwardly.

Another object is to provide such a hat stay which can be adjusted to provide different elevations of the crest of the front portion of the hat crown as desired.

Other objects and advantages will be apparent from the following description and the accompanying drawing in which

Fig. 1 is a perspective elevational view of the hat stay forming the subject of the present invention and showing the same arranged in a hat of the fedora type, the hat being illustrated by broken lines and the view being taken from the front left side of the hat.

Fig. 2 is an enlarged fragmentary vertical longitudinal central section through the front

portion of the hat stay and hat shown in Fig. 1, the hat in Fig. 2 being illustrated by solid lines.

Fig. 3 is a rear elevational view of the hat stay itself.

Fig. 4 is a top plan view thereof.

Fig. 5 is a view similar to Fig. 3 but on a reduced scale and showing a modified form of the invention.

10 Referring to Figs. 1 and 2, there is shown an illustrative form of felt hat of the fedora type in combination with which the hat stay embodying the present invention is employed. While the hat stay may be mounted in any suitable type or form of hat, the hat illustrated in the drawing is representative of the conventional type of fedora having a brim 10, sweat band 11, and crown 12 provided with an indentation 13 in its top and indentations 14 and 15 in the front upper portions of the crown. A hat so shaped provides a crest or ridge, indicated by the numeral 16, between the side indentations 14, 15 and the top indentation 13. As previously described, such a hat is generally grasped by placing the first finger in the front part of the top indentation 13 with the thumb in one of the side indentations 14, 15 and the index finger in the other side indentation.

In accordance with the invention, the hat stay 30 is formed from a sheet of resilient material into a member to support the hat crown and having a shape conformable to the contours of the front portion of the hat crown. For this purpose, the hat stay has a front portion 18, upper projections 35 or wings 19 and 20 and legs 21 and 22. The front portion 18 slants slightly upwardly and rearwardly as shown in Fig. 2 in conformity with the shape of the hat crown 12. The upper projections or wings 19, 20 extend rearwardly from the front portion 18 and slightly upwardly and diverge from each other. The upper edge of the projections or wings 19, 20 are turned or rolled over inwardly of the hat stay to provide a reinforcing web 23 and a rounded edge 24. It will be seen that this rounded edge 24 engages the 45 crest or ridge 16 of the hat. It will be noted that the reinforcing web 23 adjacent the front portion 18 extends rearwardly and downwardly to provide a support for the front portion of the top indentation 13 in the hat crown. The reinforcing web 23 adjacent the front portion 18 is also of substantial width and has a rear edge 25 which extends toward the rear extremities of the rounded edge 24 so that the web 23 progressively decreases in width toward said extremities. In this 55 manner the reinforcing web 23 serves as a stiffener between the projections or wings 19, 20 and maintains them in proper divergent relation so that they in turn serve to retain the desired shape of the hat crown.

60 Viewed from the front or rear it will be seen

that the rounded edge 24 defines a V-shaped notch and the crest 16 of the hat crown will conform to this contour.

The projections or wings 19, 20 are formed to provide concavities or indentations 26 and 28, respectively. These concavities 26, 28 maintain the shape of the indentations 14, 15 provided in the hat crown.

In order to maintain the elevation of the crest 16 above the hat brim 10, the legs 21, 22 of the hat stay are adapted to be inserted between the sweat band 11 and the hat crown 12. The legs 21, 22 are provided with rearwardly extending feet 29 and 30 respectively, and the bottom edges of these feet engage and are supported on the bight 31 of the sweat band 11. The legs 21, 22 extend divergently downwardly from the front portion 18 of the hat stay, and these legs with their feet 29, 30 bend to follow the contour of the sweat band 11.

An important feature of the hat stay is the opening 32 provided between the legs 21, 22. When the hat stay is mounted in a hat as shown in Fig. 1, this opening 32 is at the front of the hat and since no portion of the hat stay is interposed between the sweat band 11 and hat crown 12 at this place, there is no discomfort to the wearer and the front portion of the sweat band can adapt itself to the contour of the forehead of the wearer as if the hat stay were not present. Also, by cutting out the material of the hat stay between the legs 21, 22, a minimum of sheet material is on the inside of the sweat band and the size of the head opening of the hat is not noticeably decreased.

Another important advantage of the hat stay is that the feet 29, 30 extend rearwardly from the legs 21, 22, respectively, and prevent the hat stay from being pushed back out of operative position. Thus the feet 29, 30 serve to brace the hat stay against dislodgement. Such stability of the hat stay insures that the hat crown is properly supported at all times and particularly prevents the front of the hat crown from slanting rearwardly.

The hat stay is readily insertable and removable from the hat by bending or pulling the front portion of the sweat band 11 away from the crown 12.

The modified form of hat stay shown in Fig. 5 is similar to the form of the invention shown in Figs. 1-4 except that means are provided for decreasing the effective vertical height of the hat stay. Similar reference characters, except as distinguished by a prime exponent, are used in Fig. 5 to indicate like or corresponding parts. Referring to Fig. 5, each of the feet 29', 30' is shown as provided with a horizontal slit 33 leading from the heel toward the toe of the corresponding foot and a second horizontal slit 34 in line with the slit 33 and leading from the toe toward the heel of the corresponding foot. The slits 33, 34 are shown as being parallel to the lower edge of the corresponding foot 29' or 30' and the opposing ends of these slits terminate short of each other to leave intact a portion of the foot body 35 therebetween. However, the opposite or free ends of these slits 33, 34 extend to the corresponding vertical edge of the corresponding foot so that the tab 36 is integrally joined to the foot but may be easily torn therefrom by pushing or pulling either end of the tab 36 in a direction transverse of the plane of the foot, the portion 35 thereby being torn generally along a line joining the opposing inner ends of the slits 33, 34.

With the form of the invention shown in Fig. 75

5, the hat stay provided with the tabs 36 when placed in operative position in the front of a hat will have a greater effective vertical height between the bottom edges of the tabs 36 and the top rounded edge 24 provided on the hat stay than when the tabs 36 are torn off. In this manner the height of the crest 16 of the hat crown above the hat brim 10 can be adjusted.

While only one tab 36 is shown as provided on each of the feet 29', 30', it will be understood that any number of tabs can be provided one above the other on each foot so as to provide a plurality of adjustments. Further, any other suitable means of varying the effective vertical height of the hat stay is intended to be included within the teaching of this feature of the invention and the form of tab 36 shown in Fig. 5 is intended as illustrative only.

The hat stay is preferably made from light plastic material or any suitable semi-rigid, bendable and resilient material, so that it will properly support a hat and retain its shape.

From the foregoing, it will be seen that the invention provides a light weight hat stay which effectively retains the shape of the front portion of a hat crown, is stable in its operative position and not likely to be accidentally or unintentionally dislodged although it can be readily mounted in or removed from the hat, is mounted in the hat in a manner which does not damage the hat, and creates no discomfort to the wearer of the hat. Further the hat stay is simple in construction and inexpensive to manufacture.

I claim:

33. A hat stay for retaining the shape of a hat, said hat having a crown provided with an indentation in its top and an indentation on each lateral side of the front portion of said crown and a sweat band on the interior of said crown and secured along its lower edge thereto, said hat stay comprising a one-piece flexible sheet member having a front portion, divergent wings extending upwardly and rearwardly from said front portion and each provided with a concavity therein, a depressed web extending across the space between said wings, a continuous rounded edge portion connecting said wings and said web, the rear edge of said web being spaced a substantial distance from said front portion and the center portion of said web being of substantial width and inclining downwardly and rearwardly from the upper edge of said front portion thereby to provide a stiff yet yielding resistance to movement of said wings toward each other, divergent legs extending downwardly and rearwardly from adjacent the juncture of said wings with said front portion thereby leaving an open area between said legs at the front of the hat stay, and each of said legs having a foot portion extending rearwardly from the lower end thereof, said legs and foot portions being adapted to be arranged between said crown and said sweat band whereby the hat stay engages the interior surface of the front portion of said crown and provides a support therefor.
